UNITED STATES PATENT OFFICE.

PATRICK MILLAR MATTHEW, OF EDINBURGH, SCOTLAND.

CALENDERING-MACHINE.

SPECIFICATION forming part of Letters Patent No. 695,107, dated March 11, 1902.

Application filed October 8, 1901. Serial No. 77,993. (No model.)

To all whom it may concern:

Be it known that I, PATRICK MILLAR MATTHEW, a citizen of the United Kingdom of Great Britain and Ireland, residing at Victoria India Rubber Mills, Edinburgh, county of Mid-Lothian, Scotland, have invented Improvements in Calendering - Machines, (for which application for patent has been made in Great Britain, No. 4,360, dated March 1, 1901, and in Germany, dated June 20, 1901,) of which the following is a specification.

This invention relates to calendering-machines of the kind employed for coating fabrics with rubber and in which the rolls are arranged to rotate all at the same speed for applying what is known as a "calendered" coating or at different speeds in order to apply a friction coating of rubber, which is driven into and through the fabric.

20 The ordinary rolls employed for calendering and friction coating fabrics with rubber are adapted only for applying a coating of rubber to the entire surface of the fabrics passed through them. The rolls being housed

25 in side frames are driven by gearing outside these frames and are unsuitable for friction coating or calendering only a marginal strip along the edge of the fabric to present a fresh and strongly-adhesive surface which may be

30 advantageously used in uniting together fabrics forming parts of garments and in the manufacture of boots and shoes to facilitate the attachment of rubber soles and of goloshing-strips to canvas uppers so coated.

35 According to my invention a calendering-machine for coating a marginal strip of a fabric with rubber is so constructed that the rolls overhang or extend outside one of the side frames, while the driving-gear is placed 40 on shafts extending between the side frames, and a table provided with a guide is placed alongside the overhanging rolls to facilitate the leading in of the edge of the fabric, the guide being preferably adjustable, so that 45 any desired marginal width of rubber coating may be applied.

The invention is illustrated by the accompanying drawing, which represents the improved calendering-machine in elevation.

50 As shown by the drawing, the improved calendering apparatus comprises the usual side frames F for carrying the rolls, which are, as usual, three in number and hollow; but in lieu of extending between the side frames 55 these rolls H H' H² are so constructed that

they overhang or extend outside one of the side frames F. The steam and water pipes I for heating and cooling the hollow rolls are connected at the opposite ends in the usual way. The driving - gear composed of the 60 usual spur-wheels instead of being outside the side frames F is placed on shafts extending between these frames. The central roll H' is arranged to be driven at a uniform speed with the other rolls H H² for calendering or at higher speed for friction-coating fabrics by providing two driving-pinions G G' on the shaft J of the roll H' and arranging them to slide on a feather-key on the shaft to bring into gear either of two sets K' L' or 70 K L of driving-wheels on the shafts of the rolls H H². Alongside the overhanging rolls H H' H² is placed a table M, upon which the fabric to be coated is laid, and a suitable guide, such as N, preferably adjustable, may 75 be provided to facilitate the leading in of the edge of the fabric between the rolls H' H², so that the desired marginal width of rubber coating may be applied.

The calendering-machine is operated in the 80 ordinary way, the rubber to serve as the coating along the edge of the fabric being fed in by hand between the upper rolls H and H' and carried around in the form of a thin layer on the central roll H', by which it is 85 transferred to and pressed into the margin of the fabric passing through between the rolls H' and H².

Having now described the invention, what I claim, and desire to secure by Letters Patent, is—

1. A calendering-machine constructed with the rolls overhanging one of the side frames and their driving-gear between said frames, said machine being adapted for applying a 95 friction or calendered coating of rubber to the marginal edge of a fabric as set forth.

2. In a calendering-machine the combination with the side frames of differential-speed rolls overhanging one of said frames, driving-gear between said frames and a table placed alongside said rolls to facilitate leading in the marginal edge of a fabric between the rolls. 100

In witness whereof I have hereunto set my hand in presence of two witnesses.

PATRICK MILLAR MATTHEW.
